CLAIM

The ornamental design for an intelligent vacuum pump as shown and described.

DESCRIPTION

The patent or application file contains at least one drawing executed in color. Copies of this patent or patent application publication with color drawing(s) will be provided by the Office upon request and payment of the necessary fee.

1. Intelligent vacuum pump

1.1 : Front

1.2 : Back

1.3 : Left

1.4 : Right

1.5 : Top

1.6 : Bottom

FIG. 1.1 is a front view of an intelligent vacuum pump embodying our new design; FIG. 1.2 is a back view thereof; FIG. 1.3 is a left view thereof; FIG. 1.4 is a right view thereof; FIG. 1.5 is a top view thereof; FIG. 1.6 is a bottom view thereof.
